CLAIM

The ornamental design for a combined dishrack and drainboard, as shown.

DESCRIPTION

FIG. 1 is a perspective view from the front of a combined dishrack and drainboard incorporating my design;

FIG. 2 is a front elevation view thereof;

FIG. 3 is a right-side elevation view thereof;

FIG. 4 is a rear elevation view thereof;

FIG. 5 is a left-side elevation view thereof;

FIG. 6 is a top plan view thereof; and,

FIG. 7 is a bottom plan view thereof.

FIG. 1

FIG. 2

FIG. 3

FIG. 4

FIG. 5

FIG. 6

FIG. 7
